UNITED STATES PATENT OFFICE

CHESTER C. HOSMER, OF LONG BEACH, CALIFORNIA

BLOW-OUT PREVENTER FOR OIL WELLS

Application filed November 14, 1928. Serial No. 319,260.

My invention relates to oil well appliances and more particularly to a packing element that is adapted to be applied to the upper ends or heads of oil well casings for preventing blow-outs and which latter, it will be understood, frequently occur as a result of abnormal gas and oil pressures.

The principal objects of my invention are to generally improve upon and simplify the existing forms of blow-out preventers, to provide a device of the character referred to that is relatively simple in construction, inexpensive of manufacture, and which may be readily shifted into position to pack off the head of the casing, and further to provide a blow-out preventer having a packing member that is capable of being easily and quickly shifted into position around the drill tube and then moved upwardly or downwardly onto a seat within the housing of the device so as to produce an effective pressure-proof joint between the tube and well casing and thereby preventing the troublesome and dangerous gas and oil blow-outs that frequently occur during the drilling and operations of oil wells.

With the foregoing and other objects in view, my invention consists in certain novel features of construction and arrangement of parts that will hereinafter be more fully described and claimed and illustrated in the accompanying drawings, in which:

Fig. 1 is a vertical section taken through the center of a blowout preventer embodying the principles of my invention.

Fig. 2 is a horizontal section taken approximately on the line 2-2 of Fig. 1.

Fig. 3 is a side elevational view of the blowout preventer.

Fig. 4 is a detail section of a modified form of the bowl or collar having an internally arranged seat for the packing element.

Fig. 5 is a vertical section taken through the center of a duplex bowl or collar having upper and lower seats and chambers for the packing element.

Fig. 6 is a vertical section of a bowl or collar that may be arranged on the lower wall of the housing of the device for receiving the packing element.

Fig. 7 is a perspective view of the packing

element utilized in my improved blowout preventer and looking against the underside thereof.

Fig. 8 is a side elevational view of the form of packing element that is utilized for packing against the upper or lower seat.

Referring by numerals to the accompanying drawings which illustrate a practical embodiment of my invention, 10 designates a hollow box-like housing, preferably formed of metal, that forms the body of the blowout preventer, and detachably secured to the underside of said housing, preferably by means of bolts 11, is a plate 12.

Formed integral with the top plate of the housing 10 adjacent to one end thereof is an upwardly projecting collar or flange 13 that is internally threaded for the reception of the externally threaded lower portion of a bowl 14.

Formed in the lower portion of the bowl is a short vertically disposed cylindrical chamber 15 for the accommodation of the packing element, and formed at the upper end of said chamber is a tapered seat or shoulder 16 against which the upper end of the packing element engages when said packing element occupies the chamber 15. The opening 17 through the upper portion of the bowl 14 is of sufficient size to accommodate the coupling members and tools carried by the drill tube 18.

Formed integral with and depending from the end face of plate 12 in vertical alinement with the flange or collar 13 is a flange or collar 19 that is internally threaded for the reception of the externally threaded upper end of the well casing 20. An opening 21 is formed through the bottom of plate 12, which opening is concentric with the flange or collar 19, and the diameter of this opening is such as to permit free movement therethrough of the joint members, connections and tools carried by the drill pipe 18.

Arranged for sliding movement on the upper face of plate 12 to one side of the opening 21 is a packing element 22, preferably of the type disclosed in my copending application for U. S. Letters Patent filed August 30, 1928, Sr. No. 660,145. Said packing element

comprises upper and lower split metallic rings and a split compressible or elastic ring 23 arranged between said metal rings. The two parts of this packing element are hinged 5 to each other by a vertically disposed hinged pin 24, and where this form of packer is utilized in my improved blowout preventer this hinge pin is extended downwardly for a short distance below the under face of the 10 element, as designated by 25.

Projecting downwardly from the under face of the packing element and on opposite sides of the split or opening therein are short pins or lugs 26. The upper corner of the 15 upper end of the metal rings forming a part of the packing element is beveled or cut away to form an inclined shoulder 27 that is adapted to engage upon the inclined seat 16 within the bowl 14 when the packing element is applied to the drill rod.

Formed in the upper face of bottom plate 12 and extending outwardly in line with the center of the opening 21 is a slot 28 that is adapted to be traversed by the projecting 25 lower end 25 of the hinge pin 24 when the packing element is moved backwardly and forwardly within the housing of the blowout preventer, and formed in the upper surface of the bottom plate 12 to the sides of this 30 centrally arranged slot 28 are slots 29 that diverge as they approach the opening 21.

Parallel shoulders 30 are formed on the inside of the forward ends of the diverging slots 29 and which shoulders terminate at 35 approximately diametrically opposite points above the opening 21 in bottom plate 12.

The means utilized for forcing the packing element forwardly through the housing into engagement with the drill tube 18 includes a plate 31 that is mounted for sliding movement on top of the bottom plate 12 40 behind said packing element, and which plate is carried by the inner end of a piston rod 32, which latter extends outwardly 45 through a gland or stuffing box 33 in the rear end of housing 10, and said piston rod extending into a cylinder 34 that is suitably connected to the rear end of housing 10 and said rod within cylinder carrying a small 50 piston 35.

Hydraulic pressure connections 36 are made to the cylinder 34 in order to admit pressure thereto for the purpose of moving the piston and its rod backwardly and forwardly. Obviously the rod 32 may be reciprocated in any suitable manner, for instance through the use of a rack and pinion or a quick-acting screw.

The rearward or outward movement of 60 plate 31 is limited by stop lugs 31a that project upwardly from plate 12 behind said plate 31.

Under normal conditions the packing element 22 occupies a position within the horizontal offset or to one side of the vertical 65

openings through which the drill tube 18 operates, such position of the packing element being illustrated by solid lines in Figs. 1 and 2. When so positioned the packing element is in closed position and the depending pins 25 and 26 occupy the slots 28 and 29. 70

In the event that the well that is equipped with my improved blowout preventer shows indications of a blowout, fluid pressure is admitted to cylinder 34 behind the piston 35 75 therein and as a result piston rod 32 carrying plate 31 is moved forwardly in the housing, thereby correspondingly moving the packing element 22. As the pins 26 that depend from said packing element pass into the diverging portions of the grooves 29 said packing element will be open and its hinged sections spread apart as it approaches the drill tube 80 85 80 so that said drill tube is received between the parts of the packing element before the pins 26 pass beyond the ends of the shoulders or parallel faces 30 at the forward ends of the diverging portions of the slots 29. As the pins 26 pass off the forward ends of the shoulders 30 the resiliency of the intermediate elastic compressible member 23 will close the parts of the packing element about the drill tube 18 and the latter is now drawn upward a short distance until the packer occupies the chamber 15 within bowl 14 with the beveled face 27 resting upon beveled seat 16.

Thus a practically fluid pressure tight joint is produced by the packing element between the drill tube and the housing and the pressure of the gas or oil that enters the housing from the casing 20 will be exerted against the under face of the packing element to compress the interposed elastic member 23, thereby maintaining a fluid pressure-tight joint. 90 95 100

When the head of the casing is packed off as just described, the gas or oil under pressure that rises within the casing 20 may be taken off through suitable outlet connections 38 that lead outwardly from the housing 10 105 and which outlets are equipped with suitable control valves. 110

In order to wash out mud or the like that may enter the housing through casing 20, water or steam under pressure may be delivered into the chamber within the housing through a pipe 39 that enters the top of said housing, preferably at a point above the packing element when the same is in its normal position. 115

In Fig. 4 I have shown a modified form of the bowl 14 that receives the packing element and in this construction said bowl is provided with a horizontally disposed flange 14a that is secured on top of housing 10 by 120 bolts or cap screws such as 14b.

In Fig. 5 I have illustrated a duplex bowl having a lower chamber 15a for the reception of the packing element with a tapered seat 16a at the upper end of said chamber 125 130

and formed in the upper portion of said bowl is a chamber 15b provided at its lower end with a tapered seat 16b.

Where this form of bowl is utilized a packing element may be applied to the drill rod 18b within the chamber 15b, which packing element bears against the tapered seat 16b and thus the packing of the head of the casing may be effected by utilizing the weight of the drill tube and parts carried thereby upon the packing element located within the upper chamber 15b.

In Fig. 6 I have illustrated a bowl 40 that is screw seated in the bottom plate 12 and which bowl receives the threaded upper end of the casing 20. Formed in the upper portion of this bowl is a cylindrical chamber 41 for the reception of a packing element and formed at the lower end of said chamber is a tapered shoulder 42 that receives a correspondingly tapered shoulder on the lower end of the packing element when the same is positioned within chamber 41 and shoulder 42. Where this form of bowl is utilized the packing off is brought about by the application of the weight of the drill tube to the packing element positioned within chamber 41.

In Fig. 8 I have shown a packing element provided at both its upper and lower outer edges with inclined or beveled shoulders 43, and which shoulders are adapted to engage against corresponding shoulders within the bowls utilized in connection with my improved blowout preventer.

The preferred form of packing element utilized in my improved blowout preventer is of the self-closing type, the closing action being brought about by the resiliency of the compressible member that is arranged between the upper and lower metal rings, but in order to insure the closing of the packing member after the same has been opened by the movement of the pins 26 in the diverging grooves 29 the adjacent end of the chamber within the housing is provided with a semi-circular face 45 that is concentric with the openings in the top and bottom of the housing so that when the packing element is moved into position to encircle the drill tube the open ends of the packing element will strike against the curved face, thereby tending to close said packing element about the drill tube.

Thus it will be seen that I have provided a blowout preventer that is relatively simple in construction, inexpensive of manufacture, and which may be easily and quickly manipulated to provide a fluid pressure tight joint between the upper end or head of the casing and the drill tube that passes therethrough, thus preventing the dangerous and objectionable blowouts that frequently occur as a result of excessive gas and oil pressures arising

from the well through the casing that is positioned within the well hole.

It will be understood that minor changes in the size, form and construction of the various parts of my improved blowout preventer for oil wells may be made and substituted for those herein shown and described without departing from the spirit of my invention, the scope of which is set forth in the appended claims.

I claim as my invention:

1. In a blowout preventer for oil wells, a housing adapted to be applied to the upper end of the well casing, said housing being provided with openings for the accommodation of the drill tube, a two-part hinged packing element arranged for lateral sliding movement within the housing and adapted to encircle the drill pipe passing therethrough, and a seat adapted to be engaged by said packing element when the same is positioned upon the drill pipe.

2. In a blowout preventer for oil wells, a housing adapted to be applied to the upper end of the well casing, said housing being provided with openings for the accommodation of the drill tube, a two-part hinged packing element arranged for lateral sliding movement within the housing to one side of the openings therein and adapted to encircle the drill pipe passing therethrough, a seat adapted to be engaged by said packing element when the same is positioned upon the drill pipe, and means for moving said packing element into engagement with the drill pipe passing through said housing.

3. In a blowout preventer for oil wells, a housing adapted to be applied to the upper end of the well casing, said housing being provided with openings for the accommodation of the drill tube, a packing element arranged for movement within the housing, said element comprising parts that are hinged to each other, and means for causing the hinged parts of said packing element to swing open for the reception of the drill tube when said element is moved toward said tube.

4. In a blowout preventer for oil wells, a housing adapted to be applied to the upper end of the well casing, said housing being provided with openings for the accommodation of the drill tube, a packing element arranged for movement within the housing, said element comprising parts that are hinged to each other, means for causing the hinged parts of said packing element to swing open for the reception of the drill tube when said element is moved toward said tube, and means for moving said packing element toward the drill tube.

5. In a blowout preventer for oil wells, a housing adapted to be secured to the upper portion of the well casing, said housing being provided with an opening for the ac-

commodation of the drill tube that enters said casing, a hinged packing member arranged for sliding movement within the housing and adapted when moved toward the drill tube to encircle the same, there being a chamber within the housing for the accommodation of the packing member when the same is applied to the drill tube, and a seat at the end of said chamber, which seat is adapted to receive the packing member when the same occupies said chamber.

6. In a blowout preventer for oil wells, a housing adapted to be secured to the upper portion of the well casing, said housing being provided with an opening for the accommodation of the drill tube that enters said casing, a hinged packing member arranged for sliding movement within the housing and adapted when moved toward the drill tube to encircle the same, there being a chamber within the housing for the accommodation of the packing member when the same is applied to the drill tube, a seat at the end of said chamber, which seat is adapted to receive the packing member when the same occupies said chamber, and means for moving said packing member into engagement with said drill tube.

7. In a blowout preventer for oil wells, a housing adapted to be applied to the upper portion of the well casing, said housing being provided with an opening for the accommodation of the drill tube, a bowl carried by said housing and arranged in the opening for the drill tube, said bowl being provided with a chamber and a seat for packing member, and a packing member arranged for movement within said housing and adapted when moved toward the drill tube to encircle the same and to occupy the chamber within the bowl when moved vertically with the engaged drill pipe.

8. In a blowout preventer for oil wells, a housing adapted to be applied to the upper portion of the well casing, said housing being provided with an opening for the accommodation of the drill tube, a bowl carried by said housing and arranged in the opening for the drill tube, said bowl being provided with a chamber and a seat for a packing member, a packing member arranged for movement within said housing and adapted when moved toward the drill tube to encircle the same and to occupy the chamber within the bowl when moved vertically with the engaged drill pipe, and means for moving said packing member into engagement with said drill pipe.

9. In a blowout preventer for oil wells, a housing adapted to be applied to the upper portion of the well casing, said housing being provided with an opening for the accommodation of the drill tube, a hinged packing member arranged for sliding movement within the housing, means for moving said

packing member toward the drill tube, and interengaging means between the packing member and housing for causing said packing member to open and receive the drill tube when moved toward the same.

10. In a blowout preventer for oil wells, a housing adapted to be applied to the upper portion of a well casing said housing being provided with an opening for the accommodation of the drill tube, a two-part hinged packing member arranged for movement within said housing and adapted when moved toward said drill tube to encircle the same, a bowl arranged on the housing around the opening therethrough for the reception of the packing member when the same is positioned on the drill tube, and outlets leading from said housing.

11. In a blowout preventer for oil wells, a housing adapted to be applied to the upper portion of a well casing, said housing being provided with an opening for the accommodation of the drill tube, a two-part hinged packing member arranged for movement within said housing and adapted when moved toward said drill tube to encircle the same, a bowl arranged on the housing around the opening therethrough for the reception of the packing member when the same is positioned on the drill tube, and a fluid pressure supply pipe leading to said housing.

12. The combination with an oil well casing, of a housing connected to said casing, which housing is provided with an opening for the accommodation of the drill tube that passes through said casing, and a hinged member arranged for sliding movement within said housing and adapted when moved toward the drill pipe to open to receive said drill pipe and then close so as to encircle said drill pipe.

13. The combination with an oil well casing, of a housing connected to said casing, which housing is provided with an opening for the accommodation of the drill tube that passes through said casing, a hinged member arranged for sliding movement within said housing and adapted when moved toward the drill pipe to open to receive said drill pipe and then close so as to encircle said drill pipe, and said housing being provided with a chamber and seat for the accommodation of said packing member when the same is positioned upon the drill tube.

14. The combination with an oil well casing, of a housing connected to said casing, which housing is provided with an opening for the accommodation of the drill tube that passes through said casing, a hinged member arranged for sliding movement within said housing and adapted when moved toward the drill pipe to open to receive said drill pipe and then close so as to encircle said drill pipe, said housing being provided with a chamber and seat for the accommodation of said pack-

ing member when the same is positioned upon the drill tube, and means for moving said packing member toward and into engagement with said drill tube.

5 15. In a blowout preventer for oil wells, a housing adapted to be connected to the upper portion of the well casing, said housing having an opening for the accommodation of the drill tube, a packing element arranged for 10 movement within said housing and normally positioned to the side of the drill tube opening, means for opening the packing element as it is moved toward the drill tube, and means for causing said packing element to 15 close about the drill tube.

16. In a blowout preventer for oil wells, a housing adapted to be connected to the upper end of the well casing, said housing having an opening for the accommodation of the 20 drill tube, a packing element arranged for lateral sliding movement bodily within the housing and adapted to encircle the drill pipe passing therethrough, and said housing being provided with a wash-out connection.

25 17. In a blowout preventer for oil wells, a housing, means for connecting the same to the upper portion of the well casing, said housing being provided with openings for the accommodation of the drill tube, and a packing element arranged for lateral sliding movement bodily within said housing and adapted to encircle the drill pipe passing therethrough.

18. In a blowout preventer for oil wells, 30 a housing adapted to be applied to the upper portion of the well casing, said housing having an opening for the accommodation of the drill tube, a packing element arranged for lateral sliding movement bodily within the 40 housing and adapted to encircle the drill pipe passing therethrough, and both ends of which packing element are provided with tapered faces that are adapted to engage corresponding seats within the housing.

45 19. In a blowout preventer for oil wells, a housing adapted to be applied to the upper portion of the well casing, said housing having an opening for the accommodation of the drill tube, a bowl connected to said housing 50 concentric with the drill tube opening therein, a packing element arranged for lateral sliding movement bodily within the housing and adapted to encircle the drill tube passing therethrough, and which packing element is 55 adapted to occupy said bowl to provide a fluid pressure-tight joint between the housing and drill tube.

In testimony whereof I affix my signature.
CHESTER C. HOSMER.
